(57) **CLAIM**

The ornamental design for a scraper for exhaust gas treatment apparatus, as shown and described.

DESCRIPTION

FIG. 1 is a top perspective view of a scraper for exhaust gas treatment apparatus showing our new design;

FIG. 2 is a bottom perspective view thereof;

FIG. 3 is a front elevation view thereof;

FIG. 4 is a rear elevation view thereof;

FIG. 5 is a top plan view thereof;

FIG. 6 is a bottom plan view;

FIG. 7 is a right side view thereof;

FIG. 8 is a left side view thereof;

FIG. 9 is a top perspective view showing the scraper for exhaust gas treatment apparatus in a position of use; and, FIG. 10 is a bottom perspective view showing the scraper for exhaust gas treatment apparatus in a position of use.

The broken lines depict environmental subject matter only and form no part of the claimed design.
